G. H. BUGENHAGEN

LADDER STOOL

Filed April 17, 1924

INVENTOR

G. H. Bugenhagen
BY *Munn & Co.*

ATTORNEY

UNITED STATES PATENT OFFICE.

GEORGE H. BUGENHAGEN, OF MINOT, NORTH DAKOTA.

LADDER STOOL.

Application filed April 17, 1924. Serial No. 707,218.

To all whom it may concern:

Be it known that I, GEORGE H. BUGENHAGEN, a citizen of the United States, and a resident of Minot, in the county of Ward 5 and State of North Dakota, have invented a new and useful Improvement in Ladder Stools, of which the following is a full, clear, and exact description.

My invention relates to improvements in 10 ladder stools, and it consists in the combinations, constructions, and arrangements herein described and claimed.

An object of my invention is to provide a 15 ladder stool of the type described, which when in operative position is rigidly braced so as to prevent the collapsing of the device.

A further object of my invention is to 20 provide a device of the type described in which the seat portion and the auxiliary legs may be folded into a compact position so as to permit the device to be disposed in a small out-of-the-way place.

A further object of my invention is to 25 provide a device of the type described, which is simple in construction, and which is durable and efficient for the purpose intended.

Other objects and advantages will appear 30 in the following specification, and the novel features of the invention will be particularly pointed out in the appended claims.

My invention is illustrated in the accompanying drawings, forming part of this application, in which

Figure 1 is a perspective view of the device, and

Figure 2 is a vertical section through the device as shown in folded position.

In carrying out my invention, I provide a 40 step ladder portion A, a seat B, and supporting legs C. The step ladder portion A consists of side members 1 and steps 2. The steps also act as reenforcing members for the step ladder.

The seat B comprises a body portion 3 and 45 angle irons 4. As clearly shown in Figure 2, the angle irons 4 are pivotally secured to the upper ends of the side pieces 1. The supporting legs 5 are operatively connected to the pieces 1 by means of a mechanism 50 shown in Figure 2. The bars composing this mechanism are arranged so as to provide a solid support to the device when the device is in operative position. The supporting legs 5 when in extended position 55 bear against the under side of the horizontal

flanges of the angle irons 4 and aid in supporting the seat portion 3.

The mechanism that connects the pieces 1 to the supporting legs 5 comprises two sets of connecting members, each set being composed of a link 6 that is pivotally secured to the upper end of the piece 1 at 7 and is secured at its other end to a link 8 at 9. The link 8 in turn is pivotally secured to the rear leg 5. It should be noted that two links 6 and two links 8 are provided, these links connecting the pieces 1 with the legs 5 in the manner just described. An arm 9' is pivotally secured to the angle irons 4 at 10 and has its free end pivotally secured to a link 11 at 12. The pins are carried by the rear legs 5 and therefore connect the links 9' and 11 to the rear legs 5. The links 6 and 11 are in turn pivotally secured to each other at 13. A link 14 connects the link 11 to the piece 1 in the same manner as the link 8 connects the link 6 to the leg 5. The link 14 is pivotally secured to the link 11 at 15 and is pivotally secured to the piece 1 at 16.

From the foregoing description of the various parts of the device, the operation thereof may be readily understood. When the device is in folded position, the mechanism that connects the legs 5 to the ladder portion A assumes the position shown by the full lines 80 in Figure 2 of the drawings. When the legs 5 are swung away from the ladder portion A, the various arms and legs will swing into the dotted line position shown in Figure 2, and thus rigidly support the device in operative position. It will be noted from the drawing that the links 8 and 14 are disposed substantially in alignment with each other when the device is in operative position. This construction prevents the legs 5 from 85 accidental movement inwardly toward the ladder portion 8. In like manner, the arms 9 are disposed substantially parallel with the links 8 and 14 when the ladder is in operative position, and thus prevent the upper 90 ends of the legs 5 from moving toward the pieces 1.

It will further be noted that the legs 5 and the pieces 1 are of substantially the same length and that the legs 5 are swung into a 105 position adjacent to the legs 1 and parallel therewith when the device is in inoperative position. The same movement that swings the legs 5 toward the pieces 1 also swings the seat 3 from a horizontal position into a 110

plane parallel with the plane of the ladder portion A. It will therefore appear that the device when in inoperative position takes up very little space. The legs 5 are held apart by the rungs 17 in the same manner as the pieces 1 are held apart by the steps 2.

The steps 2 and the seat 3 permit the device to be used as an ordinary step ladder. The device is also of such a height that it is adapted to be used as a kitchen stool. The device is very simple in construction and makes use of a novel means for bracing the legs 5 so as to prevent the accidental movement of the legs while the device is being used.

I claim:

1. A ladder stool comprising a ladder portion, a seat pivotally secured to said ladder portion, supporting legs for said seat and means including links connecting said ladder portion, seat, and legs together, said means being adapted to swing said ladder portion, seat, and legs into parallel relation with respect to each other, and to swing said legs away from said ladder portion, and into a position to support said seat, certain of said links being disposed in alignment with each other when said legs are in extended position, whereby said legs are locked in extended position.

2. A ladder stool comprising a ladder portion, a seat pivotally secured to said ladder portion, supporting legs for said seat, links

pivots secured to each other intermediate their ends and having one of their ends pivotally secured to said ladder portion and one of said legs respectively, a second set of links pivotally secured to the free ends of said first named links and having their free ends pivotally secured to said ladder portion and said leg respectively, said last named links adapted to be swung into substantial alignment with each other when said legs are in extended position, whereby said legs are locked in extended position.

3. A ladder stool comprising a ladder portion, a seat pivotally secured to said ladder portion, supporting legs for said seat, links pivotally secured to each other intermediate their ends and having one of their ends pivotally secured to said ladder portion and one of said legs respectively, said second set of links pivotally secured to the free ends of said first named links and having their free ends pivotally secured to said ladder portion and said leg respectively, said last named links adapted to be swung into substantial alignment with each other when said legs are in extended position, whereby said legs are locked in extended position, and irons connecting said seat to said legs, whereby said seat is swung into operative position when said legs are swung away from said ladder portion.

GEORGE H. BUGENHAGEN.
